(57) **CLAIM**

The ornamental design for a pickup tine, as shown and described.

DESCRIPTION

FIG. 1 is a perspective view of a pickup tine showing my new design.

FIG. 2 is a left side view of a pickup tine showing my new design.

FIG. 3 is a right side view of a pickup tine showing my new design.

FIG. 4 is a top view of a pickup tine showing my new design.

FIG. 5 is a bottom view of a pickup tine showing my new design.

FIG. 6 is a front view of a pickup tine showing my new design.

FIG. 7 is a rear view of a pickup tine showing my new design.

FIG. 8 is a cross sectional view taken along line 8—8 of FIG. 4 of a pickup tine showing my new design; and,

FIG. 9 is a cross sectional view taken along line 9—9 of FIG. 2 of a pickup tine showing my new design.

Any shading and cross-hatching are not features of the design but are utilized to illustrate the surface contours of the pickup tine in the drawings.

The broken line showing is for illustrative purposes only and forms no part of the claimed design.
